UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

43,564.

Specification for Design.

Patented Feb. 18, 1913.

Application filed October 24, 1912. Serial No. 727,619. Term of patent 7 years.

To all whom it may concern:

Be it known that I, WILLIAM C. CODMAN, a subject of the King of Great Britain, residing at Providence, in the county of Providence and State of Rhode Island, have invented a new, original, and ornamental Design for Handles for Spoons, Forks, or Similar Articles, reference being had to the accompanying drawing.

Figure 1 in the drawing is a view of the

obverse side of the handle, showing my design. Fig. 2 is an enlarged detailed perspective view.

I claim

The ornamental design for a handle for spoons, forks or similar articles.

WILLIAM C. CODMAN.

Witnesses:

ADA E. HAGERTY,
J. A. MILLER.
